Primary Examiner — Mark Goodwin*(74) Attorney, Agent, or Firm* — Patent Law & Venture Group; Gene Scott(57) **CLAIM**

The ornamental design for a bracket for designating direction, as shown and described.

DESCRIPTION

FIG. 1 is a perspective view of a bracket for designating direction showing my new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof shown in use condition engaging a rod; and,

FIG. 6 is a bottom plan view thereof.

The broken lines illustrating the rod in FIG. 5 form no part of the claimed design.
